AEROPLANE

Jakob Hojnowski, Nekoosa, Wis.

Application November 30, 1934, Serial No. 755,475

2 Claims. (Cl. 244—76)

This invention relates to certain new and useful improvements in aeroplanes.

An important object of the invention is to improve the motor drive of aeroplanes wherein the motor in the form of an internal combustion engine has an extended drive shaft carrying a multiple pulley block and laterally positioned driven shaft with a propeller blade on each driven shaft and belt drive connections between the pulley block and driven shaft for the lessening of driving noises incident to the operation of the propeller blades.

A further object of the invention is to provide an aeroplane wherein the wings are provided with ailerons adapted for automatic operation when the aeroplane laterally tilts for bringing the same to an even keel by means of a transversely shiftable weight member gravitationally shifting in directions laterally of the aeroplane when the latter tilts to either side for the operation of the ailerons.

A further object of the invention is to provide stabilizing devices of the foregoing character wherein the ailerons are adapted to be operated by a pivotally suspended member functioning as a pendulum for restoring the aeroplane to an even keel when tilted laterally.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a top plan view, partly broken away of an aeroplane constructed in accordance with the present invention and showing the multiple belt drive from the motor shaft to the laterally positioned propeller shaft, the stabilizing ailerons carried by the wings and the operating means therefor;

Figure 2 is a fragmentary perspective view of the tank or weight shiftable laterally of the aeroplane for the operation of the ailerons for restoring the aeroplane to an even keel from laterally tilted positions;

Figure 3 is a side elevational view of another form of gearing interposed between the laterally shiftable weight and ailerons for increasing speed of movement of the latter when the aeroplane tilts laterally;

Figure 4 is a front elevational view of the aeroplane illustrated as laterally tilted with the ailerons in operative positions for restoring the aeroplane to an even keel;

Figure 5 is a detail sectional view taken on line 5—5 of Figure 4;

Figure 6 is a side elevational view of the aeroplane, partly broken away and shown in section, illustrating the aeroplane in a downwardly tilted position with the ailerons shifted to a position for restoring the aeroplane to an even keel;

Figure 7 is a top plan view of another form of aeroplane wherein the propeller blade is mounted directly on the motor shaft, the aeroplane being illustrated as tilted laterally and the ailerons shifted to operative position for restoring the aeroplane to an even keel;

Figure 8 is a diagrammatic top plan view of an aeroplane, similar to Figure 1, wherein the laterally positioned propeller shafts are housed within a casing;

Figure 9 is a fragmentary top plan view of an aeroplane, partly broken away and illustrating a pivotally suspended weight for the operation of ailerons for restoring the aeroplane to an even keel from laterally tilted positions; and

Figure 10 is a detail view of the aileron operating mechanism, shown in Figure 9.

Referring more in detail to the accompanying drawings and particularly to Figures 1 to 6, the reference numeral 15 designates the fuselage of an aeroplane provided with upper and lower wings 16 and 17 respectively, an elevator 18 at its rear end and a motor 19 at its forward end. The motor includes a drive shaft 20 upon which a multiple pulley block 21 is fixed.

The aeroplane is equipped with a pair of propeller blades 22 mounted on driven shafts 23 positioned laterally of the drive shaft 20 and the mounting for the driven shafts 23 is shown more clearly in Figures 1, 4, and 5. Each shaft 23 is mounted in a pair of spaced supports 24 of channel formation in cross-section and of general U-shape, the outer end of each support 24 being closed as at 25. A bearing block 26 for the shaft 23 is shiftably mounted in the outer end of each support 24, being guided therein by the channel formation of the support and said blocks 26 are shiftable in the support by means of the adjusting screws 27 having a swivel connection 28 with the block 26 and threaded through the block 29 anchored in the inner end of the support 24, the screw 27 being operated by the handle 30. Each support carries an oil or grease cup 31 for the lubrication of the shaft 23.

As shown more clearly in Figure 1, a multiple pulley block 32 is carried by each shaft 23 in transverse alignment with the pulley block 21 on the motor shaft 20 and said pulley blocks 20 and 32 are shiftably mounted in the supports 24 by means of the adjusting screws 27.

32 are connected by means of endless belts 33. The belt drive between the motor shaft 20 and the laterally positioned propeller shaft 21 provides a single drive for the two propellers and also operates to lessen the noise incident to a gear drive and the driven shaft adjusting means provides proper tension on the drive belt 33 for the positive operation of the driven propeller shaft.

As shown in Figures 1 and 4, the trailing edges 10 of the wings 16 and 17 are respectively provided with ailerons 34 and 35 connected by rods 36 for simultaneous operation and the operating means for said ailerons 34 and 35 is shown more clearly in Figures 1 and 2. A gas tank for the motor 19, 15 or a weight 37 is carried by a wheeled carriage 38 mounted on trackage 39 extending transversely of the fuselage 15 and the carriage 38 is provided with an upstanding fork 40 at one side thereof. The shaft 41 extending longitudinally of the 20 fuselage is journaled in bearings 42 and carries a crank arm 43 at one end cooperating with the fork 40 while the other end of the shaft 41 carries a bevelled gear 44. A shaft 45 is journaled longitudinally of each end of the wing 17 and to which 25 the ailerons 35 are rigidly secured, a pinion 46 being secured to each adjacent end of the two shafts 45 for meshing engagement with the bevelled gear 44. It will therefore be seen that when the aeroplane tilts laterally, the gas tank or 30 weight 37 will move over the trackage 39 and the fork 40 of the carriage operates the crank arm 43 of the shaft 41 to rotate the bevel gear 44 and impart reverse rotation to the two shafts 45 to cause the ailerons 34 and 35 at each side of 35 the longitudinal axis of the aeroplane to be respectively raised or lowered as illustrated in Figure 4 for restoring the aeroplane to an even keel from a laterally tilted position.

A modified form of connecting means between 40 the laterally shiftable weight 37 and the aileron operating shaft 45 is shown in Figure 3, this connection operating to produce increased speed of movement to the ailerons relative to movement of the weight. The shaft 41a carries a crank 45 arm 43a adapted for engagement with the fork 40 of the wheeled carriage and said shaft 41a carries a gear wheel 47 for meshing engagement with a pinion 48 on the shaft 49 that carries a bevel gear 44a that meshes with the pinions 46 50 of the shaft 45.

The forward and trailing edges of the wings 16 and 17 are provided with additional ailerons for bringing the aeroplane out of a nose dive and into even keel with operating means therefor and 55 as shown in Figures 1 and 6, the leading edges of the wings 16 and 17 respectively carry downwardly moving ailerons 50 and 51 while the trailing edges of the wings 16 and 17 respectively carry upwardly moving ailerons 52 and 53. A tank or 60 weight 54 is shiftable longitudinally of the fuselage 15, being located adjacent the rear end thereof and being mounted on trackage 55 and said weight 54 carries laterally directed arms 56, each having a link connection 57 with an arm 58 65 projecting radially of a shaft 59 journaled in the lower wing 17 to which ailerons 53 are secured.

Arms 51a and 52a respectively project from the pivot bearings of the ailerons 51 and 52 and are connected by a link. Ailerons 50 and 51 are connected by a link 61 while the ailerons 52 and 53 are connected by a link 62. It will therefore be seen that when the aeroplane enters a nose dive, the weight 54 will be shifted forwardly for the operation of the shaft 59 for simultaneously raising trailing ailerons 52 and 53 by their link con-

nexion 60 between the ailerons 52 and aileron 51, the ailerons 50 and 51 simultaneously lowered.

The elevator 18 is automatically operated to aid in bringing the aeroplane out of a nose dive and as shown in Figures 1 and 6, a weighted receptacle or basket 63 is pivotally suspended from the upper end of the fuselage on a shaft 64 and has a link connection 65 with an arm 66 carried by the bearing for the elevator, rearward swinging movement of the weighted basket 63 being limited by the transversely extending abutment bar 67. As shown in Figure 6, the aeroplane is tilted downwardly and the basket 63 swung forwardly for the elevation of the rudder 18.

The aeroplane illustrated in Figure 7 is of the mono-plane type and the single propeller 68 is directly mounted on the shaft of the motor. The transversely shiftable weight 37a carries a fork 40a while the ailerons 34a on the trailing edge of the wings 16a each fits to a shaft 45a carrying a bevel pinion 48a at adjacent ends. The side connection between the weight 37a and shaft 45a is of the form illustrated in Figure 3 and includes the bevel gear 44a on the shaft 49 meshing with the bevel pinions 46a, the connection further including the pinion and gear combination 48 and 47. The aeroplane is illustrated in a laterally tilted position with the weight 37a laterally shifted for the operation of the shafts 45a and the ailerons 34a, one aileron being lowered and the other one raised and operating to restore the aeroplane to an even keel to bring the same out of the laterally tilted position.

In the diagrammatic showing in Figure 8, the nose end of the aeroplane 69 is provided with a housing 70 enclosing laterally positioned shafts for the dual propellers 22a and the belt drive with the motor shaft. This form of the invention embodies ailerons for restoring the aeroplane to an even keel out of laterally tilted positions and the operating mechanism for such ailerons 71 is shown more clearly in Figures 9 and 10. A shaft 72 is journaled longitudinally of the fuselage 69 and carries a weighted basket 73 adapted to swing laterally of the fuselage to effect reverse oscillations of the shaft 72, this arrangement being clearly shown in Figure 10. The shaft 72 carries a bevel gear 74 at its forward end that meshes with bevel pinions 75 fixed to cross shafts 76 journaled longitudinally of each lateral wing spread and to which shaft 76 the ailerons 71 are fixed. It will be observed from an inspection of Figure 10 that when the weighted basket 73 swings laterally as indicated by dotted lines, the shafts 76 are reversely rotated for respectively raising or lowering the ailerons 71.

From the above detailed description of the invention, it is believed that the construction and operation thereof will at once be apparent, and while there are herein shown and described the preferred embodiments of the invention, it is nevertheless to be understood that minor changes may be made therein without departing from the spirit and scope of the invention as claimed:

I claim:—

1. In a biplane of the character described, a fuselage, wings on the fuselage, ailerons carried by the leading and trailing edges of the wings for bringing the aeroplane out of a nose dive, link connections respectively between the ailerons at the leading and trailing edges of the wings, diagonal link connections between an aileron at the leading edge of a wing and an aile-

ron at the trailing edge of the other wing, and a weight slideable longitudinally of the fuselage and having link and arm connections with the ailerons at the trailing edge of one wing for simultaneous operation of the ailerons.

2. In a biplane of the character described, a fuselage, wings on the fuselage, ailerons carried by the leading and trailing edges of the wings for bringing the biplane out of a nose dive, link connections respectively between the ailerons at

the leading and trailing edges of the wings, an arm extending angularly from an aileron at the leading edge of a wing, an arm extending angularly from an aileron at the trailing edge of the other wing, a link connection between said arms, and a weight slideable longitudinally of the fuselage and having a link connection with the ailerons at the trailing edge of one wing for simultaneous operation of the ailerons.
